(57) **CLAIM**

The ornamental design for scissor handles, as shown and described.

DESCRIPTION

FIG. 1 is a first isometric view of a first embodiment of the claimed design;

FIG. 2 is a second isometric view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof.

FIG. 9 is a first isometric view of a second embodiment of the claimed design;

FIG. 10 is a second isometric view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

The ornamental design which is claimed is shown in solid lines in the drawings. The broken lines in the drawings illustrate the environment of the claimed design and form no part of thereof.
